Story

UNITED STATES PATENT OFFICE.

JOHN J. IRVIN, OF BELLWOOD, PENNSYLVANIA.

DUMP-CAR.

1,134,859.

Specification of Letters Patent. Patented Apr. 6, 1915.

Application filed June 17, 1913. Serial No. 774,168.

To all whom it may concern:

Be it known that I, JOHN J. IRVIN, a citizen of the United States, residing at Bellwood, in the county of Blair and State 5 of Pennsylvania, have invented new and useful Improvements in Dump-Cars, of which the following is a specification.

This invention relates to dump cars and particularly to the mechanism for unlatching and opening the door or doors of a dump car body, whereby as the body is turned over or tilted relatively to the supporting truck, the door is held suspended and automatically swung outwardly thereby 15 allowing the contents of the car to be dumped without requiring manipulation or attention on the part of the operator other than that necessitated in the operation of tilting the body.

20 A further object of the invention is to provide door opening mechanism of novel construction which will operate to first unlatch the door relatively to the body and then swing the door outwardly away from 25 the body as the latter tilts toward its dumping position.

25 A further object of the invention is to so arrange the door operating mechanism that while the mechanism acts to open the door 30 at one side of the body during the tilting operation, the door operating mechanism at the opposite side of the body will not be disturbed or thrown into operation, the door at the high side of the body remaining 35 closed and latched.

With the above and other objects in view, the invention consists in the construction, combination and arrangement of parts, as will hereinafter be more fully described, 40 illustrated and claimed.

In the accompanying drawings:—Figure 1 is an end elevation of a dump car embodying the present invention, showing the car in its normal horizontal position. Fig. 45 2 is a similar view showing the first step in the tilting operation with the latch withdrawn. Fig. 3 is a similar view showing the final dumping position of the car body and the full open position of the door. Fig. 50 4 is a detail side elevation of the door bar. Fig. 5 is a bottom view of the same. Fig. 6 is a detail perspective view of the strip 9; Fig. 7 is a detail perspective view of the strip 10.

55 Referring to the drawings, A designates the car-truck, B the car body and C the car

doors, the body B having a jointed connection at 1 with the truck, the axis of the joint being shown as extending in a fore and aft direction so that the body B is adapted to tilt laterally to one side or the other as may be required. Two doors C are shown, the same being arranged at opposite sides of the body and normally arranged in vertical planes, abutting at their inner faces against the vertical side edges of the front and back of the car body as shown.

Each door C is supported at its bottom edge on the car floor 2 and is provided adjacent to its front and rear bottom corners with bolts or latches 3 rigidly fastened to the door and projecting below the bottom edge thereof where they engage keepers 4 secured to the car body in position to receive the latches 3 when the door C is at the lower limit of its sliding movement. The keepers 4 which are hollow are fastened to angle iron sills 5 fastened to the bottom of the car body and said keepers are formed with upwardly and outwardly inclined flanges forming deflecting lips which act to crowd the bolts 3 inwardly as the door slides to its closed position.

6 designates a door bar, two of said door bars being employed in connection with each door C. Therefore, in a complete car four door bars 6 are employed, two for each door. Each door bar 6 is pivotally connected at 7 to the car body and pivotally connected at 8 to the car door, the door bar 6 being normally horizontal as shown in Fig. 1 when the car body is in its normal carrying position. A convenient way of connecting the door bars 6 with the door C is shown as consisting of an angle iron saddle member having its strip 9 fastened in fixed relation to the door C while adjacent to the member 9 is an angle iron bracket 10 arranged in spaced relation to the inwardly extending flange of the facing strip 9, the parts 9 and 10 serving as oppositely arranged supports for the pivot 8 which connects the door bar 6 to the door C. The strip 9 serves substantially as a back plate which is caused to project beyond the saddle member proper and the door is thereby enabled to be secured in contacting relation with the projecting ends of said back plate.

The door bar 6 extends beyond the pivot 8 to form a door operating nose 11 having an inclined and inwardly and downwardly

sloping working face 12 which is adapted to come into contact with the member 9 during the tilting movement of the car body as will hereinafter appear. The door bar 6 is held back by means of a supporting bar 13 the upper end of which is pivotally connected at 14 to the door bar while the lower end thereof is pivotally connected at 15 to a swinging link 16 pivotally attached at its 10 opposite end at 17 to the truck A. As the car body B starts to tilt, the lower end of the supporting bar 13 comes in contact with and is arrested by a stop 18 on the truck, said stop 18 being arranged in the path of 15 the lower extremity of the supporting bar 13 the movement of which is governed by the link 16.

From the foregoing description the operation of the door mechanism will now be understood. As the body starts to tilt, the supporting bar 13 is in turn supported by the stop 18 and therefore operates to hold back the door bar 6. As the door C is supported by said door bar, the first operation 25 of the door bar is to lift the door C relatively to the car body. This has the effect of withdrawing the latches 3 from their keepers 4, moving the door from the position shown in Fig. 1 to the unlatched position shown 30 in Fig. 2. When the parts reach the position shown in Fig. 2, the inclined face 12 of the nose 11 of the door bar comes into contact with the door and prevents any further pivotal movement between the door C and 35 the door bar 6. Therefore in the further tilting movement of the car body, the door C is swung or pushed outwardly and carried from the position shown in Fig. 2 to the full open position shown in Fig. 3. The relative 40 position of the door to the car body at this stage is due entirely to gravity, but it will be seen from the construction of the door bar and its pivot, that if a boulder or other solid matter larger than the opening thus formed 45 was being dumped it would still further raise the door on its pivot forcing a larger opening for itself. During this tilting movement of the body, the door at the opposite side of the body remains undisturbed 50 for the reason that the link 16 at that side of the car swings upwardly and therefore

produces no movement of the door bar at that side of the car. Upon the return of the car body to its normal horizontal carrying position, it will be seen that all of the elements of the door operating mechanism, and the door itself, return to their initial positions illustrated in Fig. 1, by the action of gravity alone. When the body is in its normal carrying position, both of the doors are 60 closed and securely latched.

19 designates stay chains interposed between the truck A and body B at opposite sides of the center of the car for the purpose of preventing any accidental tilting of the 65 body while in transit, each of said chains being shown as comprising separable sections normally fastened together but rendered separable from each other by means of a fastening device 20 of any suitable description.

It will also be observed that no attention whatever is required with relation to the doors and other operating mechanism as all of said parts operate automatically and take 75 care of themselves, the said parts being entirely independent of the mechanism for giving the initial tilt to the car body.

What is claimed is:—

In combination a truck, a dumping car 80 trunnioned thereupon, a pair of arms fulcrumed upon the opposite sides of said car in proximity to each other, a saddle member pivotally mounted upon the outer end of each of said arms, a terminal nose formed 85 upon each of said arms disposed within said saddle member, a back plate carried by said saddle member projecting therebeyond, an oblong door carried by said back plate and projecting in contacting relation with the 90 projecting end thereof, a locking bolt projecting from said back plate, a keeper with which said bolt is adapted to engage, and means engaging the inner ends of said arms whereby to lift the latter when said car is 95 dumped.

In testimony whereof I affix my signature in presence of two witnesses.

JOHN J. IRVIN.
